CIGARETTE MACHINE FEED

Charles Arelt, Richmond Hill, N. Y., assignor to
 American Machine & Foundry Company, a
 corporation of New Jersey

Application June 11, 1942, Serial No. 446,585

26 Claims. (Cl. 131—109)

1

This invention relates to tobacco feeding mechanism for cigarette making machines of the continuous rod type.

It is common practice in the cigarette tobacco feeding art to use what is described as a carded feed drum for the purpose of removing continuously a layer of tobacco from a tobacco supply held in a suitable hopper. Another carded roll, known as a refuser drum, is usually employed in conjunction with this feed roll and is positioned above and close to the carded feed drum. The carded refuser drum rotates in the same direction as the feed roll which will cause their adjoining surfaces to travel in opposite directions. In this manner the refuser drum acts to brush or sweep back all tobacco picked up by said feed drum extending above a certain predetermined height.

Although this prior structure operated to feed tobacco successfully, it was not entirely satisfactory because the refuser drum would sometimes remove more and sometimes less tobacco from the feed drum than was desired. In some cases this was due to the carding of the refuser roll being irregularly worn around its circumference. When this occurred there would be irregular quantities of tobacco on the feed drum and this would eventually show up in the completed cigarette rod. Another objection to this structure was that the tobacco removed would build up and form a compacted roll just in front of the area between the refuser drum and the feed drum. The rotation of the feed roll and refuser drum would eventually cause this accumulation to rotate. This rotating roll of accumulated tobacco had a refusing or sweeping effect upon the tobacco carried up by the carded feed drum which would result in a subnormal quantity of tobacco passing between the feed drum and the refuser drum.

It was also found that every now and then a mass of this compacted accumulation would be caught by the carded feed drum and pulled past the refuser drum. This obviously resulted in too much tobacco being fed toward the rod forming mechanism.

As a result the old feed functioned but it had the disadvantage that it would not feed tobacco with the great degree of uniformity and regularity that is desired today.

In order to give the public cigarettes of constant density and accurate weight it is highly desirable to have a cigarette feed which can be relied on to operate with constant uniformity.

Various attempts have been made in the past

2

to obtain a more uniform feeding of cigarette tobacco. Many of these have been directed to the means used in feeding tobacco toward the carded feed drum. Others have tried to remove short particles of tobacco from the tobacco supply on one side of the feed drum and distribute them on the other side thereof. Some even have avoided entirely the use of a single feed drum. All such attempts have had their individual advantages no doubt, but the optimum of uniformity was not attained.

The present inventor's approach to this problem of uniform feeding has been entirely different from that of his predecessors, and after much effort he has provided a device herein-after described which solves the feeding problems mentioned.

It is therefore a main object of this invention to provide a feed device which will feed tobacco with greater uniformity than has heretofore been considered possible.

Another object is to provide an improved refuser roll which operates over a substantial area along the periphery of the feed drum to sweep excess tobacco therefrom.

A further object is to provide a refuser roll which will rotate at different rates of speed with the result that the feed drum will feed a constantly uniform layer of tobacco.

30 A further object is to provide improved tamping and sweeping means adjacent the feed drum to provide a predetermined uniform quantity of tobacco immediately in front of the refuser member.

35 Another object is to provide a refusing member which oscillates over the feed drum to refuse tobacco thereon a plurality of times.

A further object is to provide a single segment multiple acting refusing device.

40 Another object is to provide an improved sweeper and tamper immediately in front of the refuser.

A further object is to provide a combination of refusing devices which will coact with a feed drum to feed a uniform quantity of tobacco in the direction of a rod forming mechanism of a cigarette machine.

Another object is to provide a rake which will have a severing or shearing action and which will also act as a compactor.

A further object is to provide an improved non-rotating refusing or sweeping member for governing the quantity of tobacco fed by a feed drum.

55 Another object is to provide an improved re-

fuser drum for a cigarette machine which will use only one portion or segment thereof with which to refuse all excess tobacco.

Other objects and features of the invention will appear as the description of the particular physical embodiment selected to illustrate the invention progresses.

In the accompanying drawings, which form a part of this specification, like characters have been applied to corresponding parts throughout the several views which make up the drawings, in which:

Fig. 1 is a sectional end elevation of a continuous rod cigarette machine tobacco feed;

Fig. 2 is an end elevation of the operating mechanism of the tobacco feeding and refusing units;

Fig. 3 is a rear view of the same as seen from line 3—3 of Fig. 2;

Fig. 4 is an end elevation of a modified form of a single segment refuser member; and

Fig. 5 is an end elevation of another modified form of a single segment refuser member.

Referring to Fig. 1, the cigarette machine tobacco feed consists of a feed housing 10 which by means of a feed drum 11 and a refuser drum 12 is divided into a tobacco feed chamber F and a tobacco distributing chamber D. The bottom of said feed chamber F is formed by a continuously moving endless belt 14 driven by a pulley 16 in the direction indicated by the arrow and running over a guide plate 18 and an idler roller 20, all of which are supported by a suitable frame 22 of the tobacco feed.

The tobacco mass T in the feed chamber F, due to action of belt 14, bears against the continuously rotating feed drum 11, thereby filling the carded surface of the latter with tobacco which is later extracted in the usual manner by means of a rotating picker fan 24 located in distributing chamber D. Said picker fan, in conjunction with a suitably mounted stationary concave 26, showers the tobacco onto a continuously moving feed belt 28 which in turn delivers this layer of showered tobacco onto a pin roller 30 coacting with a compressing roller 32, and the tobacco is forwarded through a concave 34. A picker roller 36 is provided for removing the tobacco from pin roller 30 in a conventional manner and showers said tobacco through a chute 38 down upon a paper web P. Paper web P travels transversely beneath chute 38 through a conventional guide channel 40 and is later on formed into a continuous cigarette rod in a manner well known in the art.

One of the most important features of an automatic tobacco feed lies in the uniformity with which it feeds tobacco. This uniformity of feeding by feed drum 11 depends largely on the action and construction of the refuser drum which refuses the undesirable excess of tobacco picked up by said feed drum.

In Fig. 1, refuser drum 12 is actuated in such a way as to pass over the same portion of the feed drum twice, thereby imparting a double refusing action on all tobacco carried by each portion of the drum brought into the range of action of the refuser element which results in a far better control over the amount of tobacco carried by the latter than was heretofore possible. For example, as shown in Figures 1, 2 and 4, the travel of drum 12 from left to right is along an arc, approximately two inches in length. Simultaneously with the movement of drum 12, feed drum 11 also rotates and travels through an

angle subtending an arc approximately one inch in length. This means that for each inch of periphery advanced by feed drum 11 relative to refuser drum 12, the latter passes over each inch of a periphery of feed drum 11 at least twice. The instant device is not to be confused with a device such as that shown in Dearsley, U. S. Patent No. 2,214,044, where all the carding about the circumference of the refuser drum acts to refuse tobacco on the feed drum. In the present invention only one segment or portion of the refuser drum (marked S, Fig. 1) does any refusing. The rest of the refuser drum plays no active refusing role.

It has been found that the sharpness and length of the carding on the refuser drum has to be very uniform in order to obtain an unvaried delivery of tobacco. After a machine has been in operation for a time, some of the carding on the refuser drum will become dull while other portions will be worn and shorter. As a result, the feed will not be as uniform as it was originally and this lack of uniformity will show up in the ultimate cigarette rod because the dull and short carded portions of the refuser drum will not remove as much tobacco from the feed roll as the sharper and longer carding. Tobacco of varying quantities will therefore be delivered to the rod forming mechanism.

By having only a short portion or segment of the drum 12 act as the exclusive refusing agent the inventor has avoided nonuniformity, due to the above cause, since all the tobacco will be refused by the same section of the refuser regardless of whether the carding be dull or sharp, short or long. Furthermore, by oscillating the refuser in the manner hereinafter described the inventor obtains a double refusing on all tobacco delivered to the rod forming mechanism.

As will be hereinafter brought out, a continuous roll such as shown in Fig. 1, instead of segments such as shown in Figs. 4 and 5, has the advantage that when the carding of the refusing section of the feed drum becomes worn, the drum can be rotated on its support by removing the gear 60 to present a new unworn segment of carding for performing the refusing operation and gear 60 can then be replaced. This process can be continued until the carding all around the drum has been dulled and worn. As a result, the life of the refuser drum is much greater and there will be no loss in uniformity due to this more complete use of each refuser drum.

Feed drum 11 is mounted on a shaft 42 supported by suitable bearings of frame 22. Said shaft is driven continuously by means of a gear 44 meshing with a gear 46 (Fig. 2) mounted on a shaft 48 which carries another gear 50. Gear 50 engages with a suitable source of power such as the main drive of the cigarette machine (not shown).

Refuser drum 12 is provided with conventional carding and is mounted on a shaft 52 which is supported by a pair of arms 54 loosely mounted on shaft 42. The hubs of said arms are provided with eccentric bearings 56 for the purpose of raising or lowering the refuser drum to adjust or regulate the distance or space between refuser drum 12 and feed drum 11. For more rigid support and better guidance, shaft 52 on one end is also supported by a two-part adjustable arm 58 which is likewise loosely mounted on shaft 42.

Refuser drum 12 is driven by means of a gear 60 mounted on one end of shaft 52. Gear 60 meshes with a gear 62 which in turn is driven

by a gear 64 (Fig. 2) mounted on a shaft 66 supported by frame 22 and a suitable bearing link 68. Link 68 also supports one end of another shaft 70 which is also supported by bearings in frame 22. Shaft 66 is driven by means of a sprocket 72 which through a chain 74 is driven by a sprocket 76 (Fig. 2) mounted on a shaft 78 carrying a gear 80 which meshes with gear 50. The latter, as heretofore mentioned, may be connected with the main drive of the machine (not shown).

The oscillating movement of the refuser drum 12 is accomplished by means of a pair of eccentrics 82, each of which by an adjustable connecting rod 84 is connected with shaft 52. Said eccentrics are mounted on shaft 70 which is driven by a gear 86 meshing with a gear 88 attached to sprocket 72 on shaft 66.

The rotation of the refuser drum 12 is not at a uniform speed because during its forward and rearward movements with respect to the continuous forward or counterclockwise movement of feed drum 11 in the illustrated embodiment, gear 60 moves rearwardly and forwardly relative to the continuous clockwise moving gear 62 with which it engages. During the rearward movement of drum 12 (to the right in Figure 2), the rolling of gear 60 on gear 62 tends to retard the rotation of the drum to a minimum or even turn it backwardly; during the forward movement of refuser drum 12 (to the left in Figure 2), the rolling of gear 60 on gear 62 tends to turn drum 12 forwardly or counterclockwise and thus accelerate the rotation of the drum. It will be seen that the rearward and forward movement of the refuser drum 12 and the concurrent rolling of gear 60 on gear 62 tends to respectively counteract and supplement the turning of refuser drum 12, because of the movement of gear 62 on which gear 60 travels.

By a suitable proportioning of the extent of oscillation of drum 12 and thus the extent of travel of gear 60 during each stroke, and the extent of movement of gear 62 during each stroke, if as indicated in Figure 2, it will be apparent that it can be arranged that during the major part of the rearward movement of drum 12 the backward turning of drum 12 due to the rolling of gear 60 on gear 62 will equal the forward turning of the drum 12 due to the movement of gear 62. Consequently under such conditions drum 12 will not turn on its axis but will tend to remain stationary for this portion of the stroke.

As mentioned above the oscillatory movement of the refuser drum is not uniform, the drum 12 being stationary at the dead center position of the eccentrics 82 and increasing or decreasing in speed from the mid-points between these positions. With suitable proportioning as above mentioned for the major portion of its rearward stroke, the drum 12 and gear 60 will travel in the same direction as gear 62 and through the same distance at the same time so that the drum 12 will not be rotated during this portion of the rearward stroke. However, during the forward stroke of the refuser drum 12 (from right to left, Figures 1 and 2), as gears 60 and 62 are moving in opposite directions, refuser drum 12 will be turned very rapidly in the counterclockwise direction to complete a single rotation of the drum during a single oscillation.

A conventional constantly revolving cleaning fan 90 is provided to prevent any particles of tobacco from adhering to refuser drum 12. Said cleaning fan is mounted on a shaft 92 which is

driven by means of a pulley 94 and a belt 96 (Fig. 3) from any suitable driving source of the machine. In order to enable said fan 90 to maintain its contact with refuser drum 12 during the oscillating movement of the latter, shaft 92 is supported by two pairs of arms 98 and 100 respectively. Arms 98 are loosely mounted on shaft 52, while arms 100 are pivoted to a shaft 102 which is supported by suitable bearings in frame 22. Between both arms 100 and a pair of stationary brackets 104 attached to frame 22 is anchored a pair of springs 106 employed for the purpose of acting as a counterbalance at the turning point of each oscillating movement of the refuser drum, thus preventing vibration and assuring smooth and perfect operation. Of course said springs also reduce the load of the bearings carrying shaft 52 to a great extent. The springs are also provided with adjustable mountings 108 in order to regulate their action to any desirable degree.

In order to prevent any hollow spaces in the carding of feed drum 11 and to assure that said carding is well and uniformly filled with tobacco when contacting the refuser drum 12, a number of suitable weights 110 descends intermittently upon the tobacco mass in feed chamber F; these weights press the tobacco onto and into the carding of the continuously rotating feed drum. A number of swinging rakes 112 coacts with said weights to keep an even level of tobacco above the feed drum before contacting the refuser drum, thus preventing the accumulation of an excess quantity of tobacco around the refuser drum which would disturb the important uniformity of delivery.

The weights 110 are secured to suitably shaped arms 114, all of which are properly spaced and pivoted on shaft 102. Each arm 114 is provided with a lug 116 which rests on a rod 118 held at each end by an operating arm 120 secured to shaft 102. The latter is oscillated by means of a cam lever 122 carrying a roller 124 which engages with an eccentrically mounted disc or cam 126 secured to shaft 70. The movement of lever 122 effects a lowering and raising of rod 118 which in turn causes weights 110 to descend and ascend in the desired manner.

All rakes 112 are mounted on a bar 128 and are so arranged and spaced as to operate between the spaced weights 110. The bar 128 is secured at each end to suitably shaped arms 130. Each arm 130 carries a stud 132 to which is pivoted a guide and supporting lever 134. Supporting levers 134 are pivoted to corresponding studs 136 held by frame 22. Each arm 130 is further provided with an extending operating lever 138 (Fig. 2) pivoted at one end to a crank pin 140. Each of said crank pins 140 is secured to a corresponding disc 142, both of said discs being mounted on a shaft 144 supported by a suitable bearing bracket 146 attached to the main frame 22. Shaft 144 carries a sprocket 148 which by means of a chain 150 is driven from a sprocket 152 mounted on shaft 70.

Each rake 112 has a bent portion 112^a which has proven to be an excellent device for separating the excess tobacco from the tobacco upon which the excess rests. Tobacco has a tendency to cohere very readily. By bending the end of the rake 112 (Fig. 1) it has been found that the excess will be pushed by the substantially vertical portion of the rake 112, and the bent portion 112^a will tamp down the tobacco not so removed. The action might be described as a severing or shearing operation and avoids gouging out large quantities of tobacco located below

the excess. In this way there is always a constant uniform layer of tobacco in front of the feed drum and refuser element.

A modified form of the invention shown in Fig. 4 illustrates a reciprocating refuser drum 212 having only one carded refuser section T which may be replaced when damaged or worn. The refuser drum 212 is supported and operated in substantially the same manner as refuser drum 12 shown in Fig. 1, and only the carded section T is used to perform the refusing operation. The uncarded portion U of the refuser drum acts to hold the measured tobacco in position on the feed drum 214 as the refuser drum returns to starting position. As already described, a plurality of refusing oscillations is provided for all tobacco carried by the carding on the feed drum 214, and the refuser drum obviously rotates a plurality of times for each rotation of the feed drum. There will be an intercycle acceleration and deceleration of refuser drum 212 as it rotates, similar to that of refuser drum 12 (Fig. 1), so that on the rearward stroke of the reciprocation of said refuser drum 212 the adjoining surfaces of the feed drum and the refuser drum will not move with respect to each other although the feed drum rotates constantly.

With reference to the modification shown in Fig. 5, the oscillating refuser element consists of a member 260, the curved lower side of which is provided with carding 262 which faces the carding on the main feed drum 264. The main feed drum is mounted on a shaft 266 constantly driven by a gear 268 meshing with a gear 270 on a shaft 272. The latter may be actuated in a suitable manner from the main drive of the cigarette machine (not shown). Refusing member 260 carries a rod 274 which is supported at each projecting end by an arm 276. Arm 276 is integral with a cam arm 278 and forms therewith a bell crank lever, the action of which controls the lowering and raising of member 260. Arm 278 carries a cam roller 280 which contacts a cam 282 freely mounted on shaft 266. Cam 282 is provided with a sprocket 284 driven by means of a chain 286 from a sprocket 288. Sprocket 288 is mounted on a shaft 290 and is actuated from the main drive of the machine (not shown). Each of said bell crank levers is pivoted on a shaft 292 supported by the upper end of another pair of spaced bell crank levers 294. Each of these bell crank levers 294 is freely mounted on shaft 266.

To maintain constant contact of roller 280 with cam 282, a suitable tension spring 302 is provided. Each lever 294 is connected by means of an adjustable rod 296 to a corresponding eccentric 298 mounted on and actuated by shaft 290. Said eccentrics impart oscillating motion to the refuser member 260. Arm 278 maintains the refuser member in its lower position during the refusing action, and at the termination of the refuser stroke lifts member 260 to its raised position where it is maintained until it returns to its starting position. The path of travel of member 260 is clearly shown by the arrows in Fig. 5. A pair of links 300 is provided in order to maintain the lower curved portion of member 260 parallel to the periphery of feed drum 264. Refuser element 260 is reciprocated back and forth a plurality of times for each rotation of feed drum 264 in order to refuse all tobacco carried by each portion of the drum brought into the range of action of the refuser element or pass over at least twice all tobacco carried by the feed drum.

It will be noted that in each of the species

shown and described herein, there is provided a plurality of refusing operations for all tobacco carried up by the feed drum because such a plurality of refusing actions will more accurately control the amount of tobacco being carried by the feed drum.

A carded section long and narrow in shape is used for the refusing operation. This holds true even where a refuser drum having carding around its entire periphery is employed because only one radial segment of the drum is employed for the actual refusing operation. Since only a very narrow carding is used to do all the refusing, it is immaterial if the teeth become dull or worn because all the tobacco will be acted on in a similar manner and the uniformity thereof will be maintained. It will be noted that the tobacco is collected by the collecting conveyor in a direction transverse to the direction in which tobacco is fed thereto, thus minimizing nonuniformity.

Applicant's rakes and tamper help to provide a layer of tobacco of uniform weight and density immediately in front of the refuser drum so that said refuser drum will always act upon the same quantity of tobacco. This is another element of the instant feed which has enabled the inventor to obtain the present high degree of uniformity for which he has striven.

In order to prevent the rakes 112 from becoming entangled with the tampers 110, there are provided flat bent plates 308 secured to the tampers 110 by means of screws 312, as shown in Figures 1 and 3. The outwardly bent portions of the plates 308 preferably are made wedge shaped ends provided with tapered faces 310. If a rake 112 tends to become improperly aligned relative to a tamper, the tapered faces 310 act somewhat as cams and direct the rakes back into proper position.

The invention above described may be varied in construction within the scope of the claims, for the particular device selected to illustrate the invention is but one of many concrete embodiments of the same. The invention therefore is not to be restricted to the precise details of the structure shown and described.

What is claimed is:

1. A tobacco feeding mechanism for a cigarette machine comprising: a rotary carded feed drum, a refuser drum extending along the length of said feed drum, a mounting for said refuser drum, means for imparting movement to said mounting constituting reciprocations circumferentially of the feed drum, and means for rotating said refuser drum one revolution for each reciprocatory cycle, said means for imparting reciprocatory movement to said refuser drum being constructed and arranged always to present substantially the same portion of said refuser drum in contact with tobacco to be refused.

2. A tobacco feeding device for a cigarette machine comprising: a rotary carded feed drum, a rotary carded refuser drum extending along the length of said feed drum, means for rotating said carded feed drum at a substantially lower predetermined rate than said refuser drum, means for rotating said refuser drum at a substantially faster predetermined rate than said feed drum, and mechanism for reciprocating said refuser drum back and forth circumferentially of the feed drum during each rotation of said refuser drum to cause the tobacco carried by the feed drum to have a plurality of refusing actions performed thereon by the same portion of the periphery of said refuser drum.

3. A tobacco feeding mechanism for a cigarette machine comprising: a rotary carded feed drum, a rotary carded refuser drum extending along the length of said feed drum, means for rotating said refuser drum at a predetermined rate which is many times faster than the rate of rotation of said feed drum, and means for reciprocating said refuser drum circumferentially about the axis of said feed drum always to present the same portion of the refuser drum into contact with the tobacco to be refused.

4. A tobacco feeding mechanism for a cigarette machine comprising: a rotary carded feed drum, a rotary carded refuser drum extending along the length of said feed drum, means for rotating said refuser drum at a predetermined rate which is many times faster than the rate of rotation of said feed drum, means for reciprocating said refuser drum circumferentially about the axis of said feed drum always to present the same portion of the refuser drum into contact with the tobacco to be refused, and means for adjustably mounting said refuser drum with respect to its driving means to present a different segment of the refuser drum into active refusing position to perform the actual refusing operation when a former segment has become worn.

5. In a cigarette machine, a tobacco feed comprising: a rotary carded feed drum, a rotary refuser drum having its center at a fixed distance relative to the center of said feed drum, means for rotating the refuser drum so that said refuser drum will make a plurality of rotations for each rotation of the feed drum, and means for reciprocating said refuser drum back and forth about the axis of the feed drum during each rotation of the refuser drum so as always to present the same segment of the refuser drum into active refusing position and to use the remaining portion of the refuser drum as a compactor when returning to the position where the refuser drum begins its forward travel to refuse excess tobacco carried up by the feed drum.

6. In a cigarette machine, a feed device for shredded tobacco comprising: a rotary carded feed drum, means for rotating said feed drum, a refuser drum arranged with its center at a fixed distance relative to said feed drum, means for imparting a plurality of rotations to said refuser drum for each rotation of said feed drum, means for reciprocating said refuser drum circumferentially about said feed drum once in each complete rotation of the refuser drum, and means for causing said refuser drum to use only one section of its circumference to refuse or sweep excess tobacco away from the feed drum during each complete cycle.

7. In a cigarette machine, a feeding device for feeding a predetermined quantity of tobacco from a supply of shredded tobacco comprising: a rotary feed drum, a refuser drum positioned above and extending along the length of said feed drum, means for driving each of said drums, and means for always placing the same section of the periphery of the refuser drum in operative relation with said feed drum to remove the excess tobacco from a part of the feeding drum.

8. In a cigarette machine, a feeding device for feeding a predetermined quantity of tobacco from a supply of shredded tobacco comprising: a rotary feed drum, a refuser drum positioned above and extending along the length of said feed drum, means for driving each of said drums, means for reciprocating the refuser drum circumferentially about said feed drum, and means for always plac-

ing the same section of the refuser drum into contact with the excess tobacco to be refused at the beginning of its reciprocation and maintaining said section out of contact with the excess tobacco as the refuser drum returns at the end of its reciprocation to its starting position.

9. In a cigarette machine, a feeding device for feeding a predetermined quantity of tobacco from a supply of shredded tobacco comprising: a rotary carded feed drum, means for imparting rotary movement to said feed drum, a refuser member having a carded refusing section positioned adjacent to said feed drum to sweep back excess tobacco picked up by said feed drum, and means for reciprocating said member about a portion of the circumference of said feed drum to effect a plurality of refusing actions over each tobacco carrying portion of said feed drum during each cycle of said refusing section.

10. In a cigarette machine having a carded feed drum and a refuser member cooperating therewith, a raking device comprising: a plurality of traveling members disposed in position to act upon the tobacco to remove all tobacco exceeding a predetermined quantity prior to the entrance of the remainder between the carded drum and the refuser member, each of said members traveling in a closed path and having the end thereof inclined at an angle to its direction of travel so as to have a shearing action when traveling away from said feed drum and said refuser member for removing excess tobacco away from the refuser member and feed drum.

11. In a cigarette machine having a carded feed drum and a refuser member cooperating therewith, a raking device positioned in front of said feed drum and refuser member comprising: a plurality of elongated arms having the ends thereof bent at an angle to the rest of the arm, and means for moving said arms away from said drum and member, said bent ends being constructed and arranged to provide means for compacting the tobacco remaining after the surplus tobacco has been pushed away by the unbent portion of each arm.

12. In a cigarette machine having a carded feed drum and a refuser drum cooperating therewith to allow only a predetermined quantity of tobacco to pass between said drums, means for reciprocating said refuser drum about the periphery of said feed drum at predetermined intervals to refuse tobacco over a substantial area of said feed drum, means controlling the operation of said refuser drum to present substantially the same portion of the refusing surface thereof for coaction with said feed drum each cycle of operation, a plurality of rakes cooperating with said feed drum, and mechanism for moving said rakes in closed paths into a position adjacent said feed drum and refuser drum.

13. In a cigarette machine having a rotary carded feed drum, a carded refuser member cooperating with said feed drum to allow only a predetermined quantity of tobacco to be fed between said carded feed drum and refuser member, means for reciprocating said refuser member about the periphery of said feed drum, mechanism for rotating said drum in timed relationship with the reciprocations of said refuser member to present portions of the peripheral surface of said drum for sweeping during each cycle of operations of said refuser member, said mechanism including driving means constructed and ar-

ranged to effect a plurality of refusing actions over each tobacco carrying portion of said drum as the result of the movement of said member thereover during each cycle of refusing operations, a plurality of rakes disposed adjacent to the feed drum and the refuser member, and means for actuating said rakes in time with the reciprocation of said refuser member to move said rakes in a unidirectional closed path in behind the excess tobacco pushed forward by said refuser member and away from said member to displace said excess tobacco a farther distance away from said feed drum and refuser member.

14. In a cigarette machine having a rotary carded feed drum, a carded refuser member co-operating with said feed drum to allow only a predetermined quantity of tobacco to be fed between said carded feed drum and refuser member, means for reciprocating said refuser member about the periphery of said feed drum, mechanism for rotating said drum in timed relationship with the reciprocations of said refuser member to present portions of the peripheral surface of said drum for sweeping during each cycle of operations of said refuser member, said mechanism including interconnected driving means constructed and arranged to effect a plurality of refusing actions over each tobacco carrying portion of said feed drum as the result of the movement of said refuser member thereover during each cycle of refusing operations, a plurality of rakes disposed adjacent to the feed drum and the refuser member, rake actuating mechanism including means for actuating said rakes in time with the reciprocations of said refuser member to move said rakes in a closed path during the non-sweeping movement of said member and locate said rakes behind the excess tobacco pushed forward by said refuser member and to displace said excess tobacco a farther distance away from said feed drum and refuser member, and means for tamping down the tobacco remaining after the rakes have removed said excess tobacco.

15. In a cigarette machine having a rotary carded feed drum and a refuser member coacting with said feed drum to allow only a predetermined quantity of tobacco to pass between said feed drum and refuser member, a plurality of individual elongated rakes positioned across said feed drum, each rake having a substantially vertical straight portion and a portion bent at an angle to the straight portion, mechanism for moving said rakes in a closed path to and away from said drum and member, said rakes being constructed and arranged for engaging with the tobacco to be raked for separating the excess tobacco from a predetermined quantity and removing said excess adjacent said drum and member while maintaining the predetermined quantity of tobacco free from disruption; and a plurality of spaced tamping members interspersed among said rake members and coacting with said bent ends of said rakes for pressing down the predetermined quantity of tobacco remaining after the excess tobacco has been removed by said rakes.

16. In a cigarette machine having a rotary carded feed drum and a refuser member coacting with said feed drum to allow only a predetermined quantity of tobacco to pass between said feed drum and refuser member, a plurality of individual elongated rakes positioned across said feed drum, each rake having a substantially straight portion and a portion bent at an angle to the straight portion for engaging with the tobacco to be raked for separating the excess tobacco from a

predetermined quantity and removing said excess while maintaining the predetermined quantity of tobacco free from disruption; a plurality of spaced tamping members interspersed among said rake members for pressing down the predetermined quantity of tobacco remaining after the excess tobacco has been removed by said rakes; and means mounted upon said tampers for preventing said rakes from becoming entangled with said tampers.

17. A feed for a cigarette machine comprising: a rotary carded feed drum, a refuser having a regular reciprocatory movement about the circumference of said drum to advance said refuser for pushing away all tobacco above a certain predetermined height from said drum and then withdraw said refuser, a plurality of individual rakes positioned at a station adjoining said refuser drum, means for moving said rakes towards said refuser concurrently with the withdrawing movement of said refuser, including means for lifting said rakes to travel them over and behind the excess tobacco piled up by each reciprocation of said refuser and for then pushing said excess tobacco still farther away from the feed drum and refuser, a plurality of tampers interspersed among said rakes, and means for causing said tampers to descend into the tobacco remaining after said excess tobacco has been removed by said rakes.

18. In a cigarette feed having a feed drum and a refuser member cooperating therewith to limit the quantity of tobacco passing between said feed drum and refuser member, a plurality of individual rakes having tobacco pushing means for removing all tobacco in excess of a predetermined quantity, tobacco leveling means associated with each of said rakes to level off the tobacco remaining after excess tobacco has been removed, and rake actuating mechanism for said rakes, including means for moving said rakes downwardly in a closed unidirectional path behind tobacco to be removed and then advance said rakes along another portion of said path to push the excess tobacco in front of said rakes away from the area in front of said feed drum and refuser.

19. The mechanical method of feeding cigarette tobacco in predetermined quantities in a cigarette machine having a conventional carded rotary drum, said method comprising: refusing the tobacco above said feed drum a plurality of times, removing the excess tobacco so refused away from said feed drum to maintain a substantially uniform level quantity of tobacco available for feeding, and then tamping down the tobacco remaining after the excess tobacco has been removed.

20. In a cigarette machine, a tobacco feed comprising: a rotary carded feed drum for removing tobacco from a tobacco supply, a refuser member having a refusing surface concentric with the surface of said feed drum mounted coaxially with said feed drum for uniformly removing tobacco in excess of a predetermined quantity from said feed drum, actuating means for causing said entire refuser member to refuse tobacco uniformly as it is moved forward and to move said refuser member entirely out of contact with the tobacco on said feed drum as said refuser member is returned to its starting position, and mechanism for rotating said feed drum in timed relationship with the movement of said refuser member to present portions of said drum for sweeping during each cycle of operations of said refuser member, said mechanism including

means constructed and arranged to effect a double refusing action over each tobacco carrying portion of said feed drum as the result of the movement of said refuser member thereover during each cycle of refusing operations.

21. In a cigarette machine, a tobacco feed comprising a rotary carded feed drum for removing tobacco from a tobacco supply, a refuser member provided with a carded refusing surface mounted coaxially with said feed drum for removing tobacco in excess of a predetermined quantity from said feed drum, means for moving said refuser member in a closed non-circular path of movement to and from and circumferentially about said feed drum to remove tobacco in excess of a predetermined quantity from said feed drum, means for maintaining all portions of said surface equidistant from said drum during the refusing movement of said member circumferentially relative to said drum, and mechanism for rotating said feed drum in timed relationship with the movement of said refuser member to present portions of the surface of said feed drum for refusing during each cycle of operations of said refuser member, said mechanism including driving mechanism for effecting a plurality of refusing actions over each tobacco carrying portion of said feed drum as the result of the movement of said member thereover during each cycle of refusing operations.

22. In a cigarette machine, a tobacco feed comprising: a rotary carded feed drum for removing tobacco from a tobacco supply, a refuser member having its center at a fixed distance relative to the center of said feed drum and provided with an active carded refusing portion for removing tobacco uniformly in excess of a predetermined quantity from said feed drum, and means for reciprocating said refuser member circumferentially about said feed drum to provide at least two refusing actions by the same carded refusing portion of said refusing member for all tobacco carried by the feed drum.

23. In a cigarette machine, a feed device for shredded tobacco comprising: a rotary carded feed drum, means for rotating said feed drum, a refuser drum having its center at a fixed distance relative to the center of said feed drum, said refuser drum having only a portion thereof effective for refusing tobacco during one complete cycle of operations thereof, means for imparting a plurality of rotations to said refuser drum for each rotation of said feed drum, means for reciprocating said refuser drum circumferentially about said feed drum once in each complete rotation of the refuser drum, and means for causing acceleration and deceleration of the rate of rotation of the refuser drum each time it makes one complete rotation whereby said portion of said refuser drum is operative to refuse tobacco.

24. In a cigarette machine, a tobacco feed comprising a rotary carded feed drum for removing tobacco from a tobacco supply, a refuser member provided with a carded refusing portion concentric with the periphery of said feed drum for removing tobacco in excess of a predetermined quantity from said feed drum, mechanism for operating said refuser member, said mechanism including means for reciprocating said entire member circumferentially about said feed drum first at one elevation adjacent said drum and then at another elevation spaced from said drum and means for maintaining said carded refusing portion of said member substantially concentric with the peripheral surface of said drum at all times,

and mechanism for rotating said drum in timed relationship with the reciprocations of said refuser member to present portions of the peripheral surface of said drum for refusing during each cycle of operations of said refuser member, said mechanism including interconnected driving means constructed and arranged to cause all tobacco carried by each portion of said drum brought into the range of action of said refuser member, to be refused a plurality of times as a result of the movement of said member thereover.

25. In a cigarette machine, a tobacco feed comprising: a rotary carded feed drum for removing tobacco from a tobacco supply, said feed drum having only a portion thereof available for refusing during each cycle, a refuser member having its center at a fixed distance relative to said feed drum for removing tobacco in excess of a predetermined quantity from said feed drum, means for reciprocating said refuser member circumferentially about the axis of said feed drum, and mechanism for rotating said refuser member once for each complete reciprocation thereof, said mechanism including means for controlling the operation of said refuser member relative to said drum to restrict successive refusing actions to the same portion only of the surface of said member.

26. In a cigarette machine, a tobacco feed comprising: a rotary carded feed drum for removing tobacco from a tobacco supply, a refuser member provided with a refusing surface concentric with the periphery of said drum, mechanism for moving said refuser member to travel said refusing surface in a closed path to and from and concentrically relative to the surface of said drum, said mechanism including means for moving said entire refusing surface of said refuser member circumferentially about said feed drum in a direction opposed to the direction of rotation of said drum to remove tobacco in excess of a predetermined quantity from said feed drum, means disposed adjacent said feed drum and refuser member to limit tobacco coming into contact with said refuser member to a predetermined quantity, and mechanism for rotating said drum in timed relationship with the movement of said refuser member to present portions of the surface of said drum for refusing by said refusing surface during each cycle of operations of said refuser member, said last-named mechanism including interconnected driving means constructed and arranged to cause all tobacco carried by each portion of said feed drum to be brought into the range of action of said refuser member to be refused by said refusing surface uniformly a plurality of times as the result of the movement of said member thereover.
